UNITED STATES PATENT OFFICE.

WALTHER AKEMANN, OF ESSEN, GERMANY, ASSIGNOR TO FRIED. KRUPP AKTIEN-GESELLSCHAFT, OF ESSEN-ON-THE-RUHR, GERMANY.

APPARATUS FOR THE ELECTRICAL LONG-DISTANCE CONTROL OF THE VALVE-GEAR OF A HYDRAULIC GUN-POINTING GEAR.

1,394,520.

Specification of Letters Patent. Patented Oct. 25, 1921.

Application filed November 19, 1920. Serial No. 425,105.

To all whom it may concern:

Be it known that I, WALTHER AKEMANN, residing at 61 Tringardstrasse, Essen, Germany, a citizen of the German Republic, have invented a certain new and useful Improvement in Apparatus for the Electrical Long-Distance Control of the Valve-Gear of a Hydraulic Gun-Pointing Gear, (for which I have filed application in Germany, filed 10 December 4, 1916,) of which the following is a specification.

This invention relates to such an arrangement for the electrical long distance control of the valve gear of a hydraulic gun pointing gear, which enables a particularly accurate adjustment of the gun barrel to be obtained. The invention is especially advantageous when the forces which are necessary to move the controlling valve are comparatively great.

The invention will be described with reference to the accompanying drawings which show diagrammatically a construction of a hydraulic elevating mechanism adjustable 25 by means of an electrical long distance control according to the present invention.

Figure 1 shows the general arrangement of the apparatus,

Fig. 2 is a detail view of certain parts on 30 a larger scale, and

Fig. 3 is another detail in vertical section.

Whereas in a similar arrangement, as described in my Patent No. 1,375,269, the receiving motor G acts directly on the gear 35 inclosed in the casing F and termed as stroke apparatus and performs the whole of the work necessary for the movement of the valve gear and the stroke apparatus, in the present invention this motor serves merely 40 in the present arrangement to operate certain parts of a circuit closing device M, N, P, Q (see Figs. 1 and 2). This circuit closing device M, N, P, Q is provided for the purpose of switching in or out of circuit, by 45 means of an automatic switch device contained in a casing R (see particularly Fig. 3) firstly a special controlling motor S, which co-operates with the stroke apparatus contained in the casing F and secondly of 50 switching into or out of circuit the magnet coils b⁴ and c⁴ of the cut off devices B and C.

A denotes the barrel of a naval gun which is mounted by means of its trunnions in a mounting A¹. In order that the elevation

can be imparted to the barrel A it is pivotally connected to the piston of a double acting hydraulic cylinder A³, which cylinder A³ is pivotally mounted and is connected by pipes a⁴ and a⁵ with electrically controlled cut-off devices B and C which are constructed in the form of valves. It is also connected by pipes which branch off from the pipes mentioned, to a controlling valve D adapted to be operated by hand and which is provided with a pipe for water under pressure and a pipe for exhausting the water and also with a hand wheel with which to operate it. The slide-valves of the cut-off devices B and C are held in their closed positions by springs and can be drawn into 70 their open positions against the pressure of these springs by means of magnet cores, which are rigidly connected to the slide-valves and can be acted on by electrically excitable windings b⁴ and c⁴. Pipes b⁶ and c⁶ connect the cut-off devices B and C with the casing of a controlling slide-valve adapted for long distance control E, which is provided with a pipe e¹ for admitting water under pressure and a pipe e² for exhausting 80 the water.

The movable part of the controlling valve E consists of a piston rod provided with three controlling pistons rigidly mounted thereon and the free end of which terminates 85 in a rack in a similar way as described in my Patent No. 1,375,269. Into the rack gears a toothed sector, which forms part of a gearing, which is contained in a casing F. The said gearing is for the purpose of rendering the movements of the piston rod of the controlling valve E on the one hand dependent on the receiver motor G of an electrical long distance controlling apparatus and on the other hand dependent on 95 the gun barrel A.

The long distance controlling apparatus has a transmitter H (see Fig. 1) which is set up at the observing station and which is constructed in the well known way so that 100 the continuous current supplied to it is transformed into three dephased currents of variable strength. These three dephased currents of variable strength are supplied by a three-phase long distance conductor J to the receiver G, which is constructed as a synchronous motor and receives its continuous current excitation from a local main K.

The transmitter H is adjusted by a milled head and a hand wheel which act upon a sun and planet gear in the manner illustrated in Fig. 1 of the accompanying drawings. The adjusting apparatus, which is adapted to be rotated by the milled head, is provided with a reading off apparatus, which indicates the adjusted range of the target and is used when the transmitter H is to have a rotation imparted to it which corresponds to the range of the target. The adjusting apparatus which is adapted to be rotated by means of the hand wheel is positively connected to a sighting telescope which oscillates about a horizontal axis and is used when it is required to eliminate the influence of an oblique position of the ship (caused for example by pitching or rolling) on the elevation imparted to the gun barrel in respect to a horizontal plane.

The gearing which is adapted to connect the piston rod of the controlling slide-valve to the receiver motor G and to the gun barrel A and which is substantially inclosed in the casing F corresponds in all parts to the device described in my Patent No. 1,375,269 so that it need not be explained largely.

The shaft a^8 , which is positively connected to the toothed sector a^6 of the gun barrel A is prolonged beyond the bevel wheel a^7 and (see particularly Fig. 2) is provided with another bevel wheel a^{12} and also a worm a^{13} . The bevel wheel a^{12} gears with a bevel wheel a^{14} , which serves to drive by means of another pair of bevel wheels a spur wheel a^{15} , which latter gears into the toothed outer edge m^1 of a revoluble disk M, which is provided with two circuit closing devices m^2 and m^3 constructed in the form of annular sectors. A revolving disk N provided in a corresponding manner with circuit closing devices n^2 and n^3 gears with its toothed edge n^1 with the worm a^{13} mounted on the shaft a^8 . About the axes of the disks M and N rotate wheels P and Q, which are each rigidly connected to circuit closing devices p^1 and q^1 respectively of pointer shape and constructed as rubbing brushes.

These circuit closing devices p^1 and q^1 are for the purpose of coming into contact with the circuit closing devices m^2 or m^3 and n^2 or n^3 by sliding thereon. The wheels P and Q are driven by the receiver G, the shaft g^1 of which is positively connected by a toothed wheel gearing g^2 , g^3 , g^4 , p^2 and a worm gear g^5 , g^2 with the wheels P and Q respectively. The ratio of transmission between the shaft a^8 and the toothed disk M is just as great as the ratio of transmission between the shaft g^1 and the spur wheel P. The ratio of transmission between the shaft a^8 and the disk N on the one hand and between the shaft g^1 and the wheel Q on the other hand is likewise equal. On the other hand the ratios of transmission of the driv-

ing gear of the circuit closing devices M and P p^1 are considerably greater than the ratios of transmission of the driving gear of the circuit closing devices N and Q q^1 .

The arrangement is also so constructed that the total range of adjustment of the receiver G and the gun barrel A in one direction or the other is corresponded to by approximately half a revolution of the disk N and of the wheel Q respectively in one direction or the other. The distance apart of the circuit closing devices m^2 , m^3 and n^2 , n^3 and also the dimensions of these circuit closing devices are so proportioned in the manner shown in the drawing, that when the disks M and N and also the wheels P and Q rotate, the pointer p^1 reaches one of the contact devices m^2 or m^3 working with it sooner than the pointer q^1 reaches one of the two circuit closing devices n^2 or n^3 , and does not quit it until the pointer q^1 has come into contact with its circuit closing device n^2 or n^3 .

The circuit closing devices m^2 , m^3 and p^1 and also n^2 , n^3 and q^1 are connected by conductors r^1 , r^2 , r^3 and r^4 , r^5 , r^6 with the automatic switch device for the controlling motor S contained in the casing R. The field winding of the motor S is excited through conductors k^{11} , k^{12} off the mains K. From these conductors branch off conductors r^7 , r^8 which serve to supply current to both the controlling and working circuits of the switch device, which latter is connected by conductors r^9 , r^{10} to the armature of the controlling motor S. In addition to this the magnet coils b^4 and c^4 (which are connected up in parallel) of the cut off devices B and C (see Fig. 1) are connected by conductors r^{11} and r^{12} to the switch device and across a switch K^1 to the local main K.

The switch device contained in the casing R (see particularly Fig. 3) contains five switch shuttles T, U, W, Y and Z provided with magnet coils t^1 , u^1 , w^1 , y^1 and z^1 and on the mutual position of the said shuttles it depends whether the motor S rotates in one direction or the other or is stationary and whether the circuit which contains the magnet coils b^4 and c^4 of the cut-off devices B and C in parallel is broken by the shuttles or not. The magnet coils t^1 , u^1 , w^1 , y^1 and z^1 of the switch shuttles T, U, W, Y and Z are each connected by their ends to the conductors r^6 , r^5 , r^4 , r^2 and r^1 in the line of each of which is situated a gap which can be bridged over by the circuit closing device q^1 , N n^2 , n^3 and p^1 , M m^2 , m^3 . The other ends of the said magnet coils are connected to the conductors r^7 and r^8 which are themselves connected to the local main K in the manner shown in the drawing. The shuttle T is provided with five circuit closing disks t^2 , t^3 , t^4 , t^5 , t^6 , of which the first two, t^2 and t^3 when in their upper position and the three last, t^4 , t^5 and t^6 when in the lowered posi-

tion are each adapted to bridge over a gap. The gaps which can be bridged over by the circuit closing disks t^2 , t^3 , t^5 and t^6 lie in the line of the conductors r^9 and r^{10} leading 5 to the armature of the motor S.

The shuttles U, W, Y and Z which are all similar are each provided with two circuit closing disks u^2 , u^3 , w^2 , w^3 , y^2 , y^3 and z^2 , z^3 , of which the first ones u^2 , u^3 , y^2 and z^2 are 10 adapted to bridge over a gap in the armature circuit of the motor S both when in the lowered and raised position of the shuttle, while the second ones w^3 , w^3 , y^3 and z^3 are adapted to bridge over a gap when 15 the shuttle is in the raised position the said gaps being located in the circuit which contains the conductors r^{11} and r^{12} and the magnet coils b^4 and c^4 of the cut-off devices B and C. The circuit closing devices which 20 are touched by the disks u^3 , w^3 , y^3 and z^3 when the shuttles U, W, Y and Z are in the raised position are also connected up in parallel in pairs in the manner shown in the drawing, so that when the switch K¹ is 25 closed (see Fig. 1) the lifting of a single one of the shuttles U, W, Y or Z is sufficient to excite both magnet coils b^4 and c^4 simultaneously.

The general arrangement of the apparatus 30 is also so designed in the manner shown in the drawing, that when the shuttles U and W and also Y and Z are in the lowered position the current which proceeds from the local main K through the conductor r^5 finds the way to the conductor r^8 leading back to the local main K interrupted, no matter whether the shuttle T is in the lowered or the raised position. On the other hand the said circuit connected to the local main K 35 and containing the conductors r^7 , r^8 , r^9 , r^{10} and the motor S, is closed every time when one of the shuttles U and W or Y and Z is in the raised and the other in the lowered position. Finally the gap which is situated 40 in the shuttle T and can be closed by the circuit closing device t^4 and lies in the line of the conductor r^8 leading to the pointer p^1 , is closed, when the shuttle T is in the dropped position.

In order to facilitate the explanation of 45 the working of the apparatus let it be assumed that the several parts of the same are in the position shown in the drawing and a different adjustment is to be imparted to the gun barrel A by means of long distance controlling apparatus.

For this purpose the switch K¹ is first 50 closed and then the transmitter H and with it also the corresponding receiver G rotated 60 to correspond to the desired different adjustment. The movement of the transmitter G causes rotation of the circuit closing device p^1 and q^1 positively connected to the motor shaft g^1 and constructed as pointers (see 65 Figs. 1 and 2).

If the armature of the receiver rotates in such a direction for example that the pointers p^1 and q^1 move in a clockwise direction, the two pointers will approach the circuit closing devices m^3 and n^3 held fast by the 70 stationary shaft a^8 . The pointer p^1 , which travels more quickly than the pointer q^1 reaches the corresponding circuit closing device m^3 first when the distance between the circuit closing devices is of the magnitude 75 stated and thereby closes the following circuit—K h^{12} r^7 t^4 r^3 p^1 m^3 r^2 y^1 r^8 h^{12} —K, so that the winding y^1 is excited and the shuttle Y is raised. At the same time the exciting circuit for the magnet coils b^4 and 80 c^4 connected up in parallel is closed across the circuit closing disk y^3 so that the cut-off devices B and C open simultaneously. At the same time the following circuit is made by the circuit closing disk y^2 ;—K 85 h^{12} , r^7 z^2 t^5 r^9 S r^{10} t^6 y^2 r^8 h^{11} —K. The motor S therefore starts and opens through the medium of the stroke apparatus contained in the casing F the controlling 90 valve E.

The opening movement of the controlling valve E may at the same time take place in such a direction that the piston rod rises and consequently water under pressure passes through the pipes e^1 , e^5 , the opened cut-off 95 device C and the force pipe a^5 and imparts the desired movement to the gun barrel. At the same time the shaft a^8 is set in rotation by the toothed sector a^6 which moves with the barrel A. 100

In the meantime the pointer q^1 has also reached the corresponding circuit closing device n^3 and now continues to slide on this latter until the receiving motor G comes to a standstill. As soon as the circuit closing 105 device q^1 and n^3 touch each other, a controlling circuit—K h^{12} r^7 u^1 r^5 n^3 q^1 r^6 t^1 r^8 h^{11} —K, which contains the magnet coils t^1 and u^1 of the shuttles T and U is closed, so that the shuttles T and U move into their raised 110 positions. The results of this are firstly that the current flowing over the circuit closing disk t^4 and the conductor r^8 to the pointer p^1 and from this latter over the circuit closing device m^3 to the magnet coil y^1 is broken, 115 so that the shuttle Y returns to its lowered position, secondly the working circuit hitherto closed across the circuit closing disks t^5 and t^6 is interrupted and a new working circuit—K h^{12} r^7 w^2 t^8 r^9 S r^{10} t^2 u^2 r^8 h^{11} —K 120 containing the circuit closing disks t^2 and t^3 is closed without the direction of rotation of the motor S altering, and thirdly the exciting circuit for the magnet coils b^4 and c^4 is now no longer closed through the circuit closing disk y^3 but by the circuit closing disk u^3 . The cut-off devices B and C consequently remain opened. The sole difference 125 is that owing to the interruption of the controlling circuit leading across the pointer p^1 130

and the circuit closing disk t^4 only the circuit closing device Q N is now effective.

The pointer p^1 can therefore make one or even several complete revolutions, without 5 the switch device R and the motor S being acted upon thereby. Only when in consequence of the continued movement of the barrel A and the shaft a^8 the disk N has hastened after the disk Q to such a degree 10 that the circuit closing devices q^1 and n^3 no longer touch each other, does any change take place of the hitherto existent state of resistance. The magnet coils t^1 and u^1 next become devoid of current and the shuttles 15 T and U pass back into the dropped positions. At the same time the pointer p^1 , which in the meantime has again moved into contact with the circuit closing device m^3 , lifts the shuttle Y again. Thus with regard 20 to the arrangement of connections R the same state of affairs is restored which existed at the beginning of the running of the motor S, when the pointer p^1 moved into contact with the circuit closing device m^3 25 for the first time. As soon as the gun barrel A has moved the disk M so far after the spur wheel P that the pointer p^1 quits the circuit closing device m^3 , the shuttle Y returns to its lowered position and the various parts of the arrangement are in their 30 original positions from which the description of the working of the apparatus was begun *i. e.* that all the shuttles are in their lowered positions and consequently all the 35 working and controlling circuits are broken. The cut-off devices B and C therefore close, and both the gun barrel A and the motor S remain stationary.

As under these conditions the armature of 40 the controlling motor S is short circuited on itself across r^9 t^5 z^2 y^2 t^6 r^{10} , it acts as a brake, and the motor S is brought to a standstill almost instantly, and so the adjusting operation comes to an end. As at 45 the conclusion of the adjusting operation the angular position of the circuit closing disks M and N positively connected to the gun barrel A is the same with respect to the pointers p^1 and q^1 driven by the receiver 50 G as at the beginning of the adjusting operation, it is clear that the gun barrel A and the receiver have been rotated through the same angle in the operations described. The gun barrel A has consequently taken 55 part in a movement which is the same as the movement of the transmitter H.

It requires no special explanation to see that the operation above described would take place in exactly the same manner but 60 with all the parts concerned moving in the opposite direction of the transmitter H and consequently the receiver motor G receives an adjusting movement in the opposite direction. The arrangement with the separate receiving and controlling motor has as 65

already stated the advantage compared with the arrangement which forms the subject matter of my Patent No. 1,375,269 that the receiving motor has only to actuate the disks P and Q of the circuit closing device 70 and not the controlling valve E. It is therefore possible, even in the case of comparatively powerful forces necessary to move the controlling valve to use a comparatively small receiving motor. Since 75 this latter has only to develop a small turning moment, the dimensions of the transmitter H and the long distance conductor J may be kept very small.

Instead of a single transmitter H embracing 80 the entire range of adjustment and a single receiver for driving the circuit closing devices P and Q two transmitters and two receivers each constructed according to the coarse and fine system may be used. 85 At the same time each of the two receivers which are mechanically independent of each other will have the driving of one of the two circuit closing devices assigned to it.

Without departing from the spirit of the 90 invention, the double circuit closing device consisting of the parts M P and N Q might also be replaced by a single circuit closing device controlling the entire range of adjustment of the receiving motor G, which would 95 result in a corresponding simplification of the switch apparatus R. The advantage of the apparatus described is however that a very high degree of accuracy can be obtained even with disks of moderate diameter, whereas the same accuracy would require disks of a very large diameter were 100 a single circuit closing device to be used.

Of course instead of a single controlling 105 motor S two motors may be used, of which the one is controlled by the circuit closing device M P and the other by the circuit closing device N Q. The connection of the two motors with the one driving shaft of the stroke apparatus contained in the casing F 110 might in this case be effected by a sun and planet gear, the middle wheels of which are driven from one of the two motors, while the planet wheel sets the said driving shaft in rotation.

Claims:

1. An electrical long distance control apparatus for the valve gear of a hydraulic gun pointing mechanism comprising the combination with a gun barrel, a sighting device, a transmitter, a receiver, means connecting said transmitter and said receiver for synchronous operation, a hydraulic gun pointing mechanism, means for supplying a hydraulic medium to said hydraulic mechanism, a system of valves for controlling said hydraulic medium, said system including a slide valve, a pair of quick acting valves, a stroke apparatus for controlling said slide valve, a circuit closing device, said 120
- 65
- 125
- 130

- circuit closing device comprising independently operatable sections, one section being connected to and operatable by the gun barrel, the other section being connected to and operated by said receiver, means connecting said stroke apparatus to said gun barrel, a controlling motor, an automatic switch, said automatic switch being electrically interposed between said circuit closing device and said controlling motor, and means connecting said controlling motor to said stroke apparatus. 2. An electrical long distance control apparatus for the valve gear of a hydraulic mechanism comprising the combination with a gun of a sighting device, an electrical distance control comprising a transmitter and a receiver connected for synchronous operation, a hydraulic gun pointing mechanism, means including a system of valves for supplying a hydraulic medium to said hydraulic mechanism, said system of valves including a controlling valve and cut off devices, a circuit closing device comprising relatively movable contacts, one set of contacts being connected to and operated by the gun, the other set being connected to and operated by said receiver, an automatic switch electrically connected to said circuit closing device, a controlling motor electrically connected to said automatic switch, means operatively connecting said motor to said control valve and means operatively connecting said cut off devices to said automatic switch. 3. An apparatus for the electrical long distance control of the valve gear of a hydraulic gun pointing mechanism, comprising a gun, a sighting device, a transmitter connected to said sighting device, a receiver electrically connected to said transmitter for synchronous operation therewith, a hydraulic gun pointing mechanism, means for supplying a hydraulic fluid to said hydraulic mechanism, a control valve and two cut-off devices for controlling said hydraulic fluid, a circuit closing device, said circuit closing device comprising two sets of contacts, one contact from each set being connected to and operated by said gun, the other contact of each set being connected to and operated by said receiver, one set of contacts operating at a greater ratio of speed than the other, a controlling motor, means operatively connecting said controlling motor to said slide valve, means connecting said slide valve to said gun, an automatic switch electrically interposed between said circuit closing device and said motor, the connection between said automatic switch and one of said sets of contacts of the circuit closing device being such that the circuit between the two is interrupted by a circuit established between the other set of contact pieces and said switch. 4. An apparatus for the electrical long distance control of a hydraulic mechanism comprising the combination with a gun of a sighting device, a transmitter connected thereto, a receiver electrically connected to said transmitter for synchronous operation therewith, a hydraulic mechanism, means for supplying the hydraulic fluids to said mechanism, valves for controlling said hydraulic fluid comprising a slide valve and a pair of cut off devices, a circuit closing device comprising two sets of contacts, an automatic switch electrically connected to said circuit closing device, said automatic switch comprising a multiplicity of switch shuttles, a controlling motor electrically connected to said circuit closing device through said automatic switch, a source of current connected to said motor and automatic switch, means connecting said switch to said cut-off devices for controlling the same, said automatic switch controlling said motor for causing it to rotate in either direction, substantially as and for the purpose set forth. 5. An apparatus for the electrical long distance control of a hydraulic mechanism comprising the combination of a gun with a sighting device, a transmitter connected thereto, a receiver electrically connected to said transmitter for synchronous operation therewith, a hydraulic gun pointing mechanism, means for supplying a hydraulic fluid to said hydraulic mechanism, a slide valve and two cut-off devices for controlling said hydraulic fluid, a circuit closing device, said circuit closing device comprising two sets of coöperating contacts, one contact from each set being operatively connected to the gun barrel, the other contact of each set being operatively connected to said receiver, an automatic switch electrically connected to the contacts of said circuit closing device, a controlling motor electrically connected to and controlled by said automatic switch, means including a stroke apparatus for connecting said slide valve to said controlling motor, means connecting said automatic switch to said cut-off devices, said automatic switch controlling the direction of rotation of said controlling motor and said automatic switch tending further to short-circuit said motor so as to cause the same to act as a brake. 6. An apparatus for the electrical long distance control of a valve gear of a hydraulic gun pointing mechanism comprising a gun, a sighting device, a transmitter connected to said sighting device, a receiver electrically connected to said transmitter for synchronous operation therewith, a hydraulic gun pointing mechanism, means for supplying a hydraulic medium to said hydraulic mechanism, a sliding control valve and two cut-off devices interposed into said supply means for controlling said hydraulic medium, a circuit closing device, said circuit closing

- device comprising two sets of contact devices, each set of contact devices co-operating with one another, one contact device from each set being connected to and operated by the gun barrel, the other contact device of each set being connected to and operated by said receiver, one set of contact devices having a greater ratio of rotation than the other, an automatic switch 5 electrically connected to said circuit closing device, said circuit closing device comprising a multiplicity of magnetically operated switch shuttles, a control motor electrically connected to said automatic switch, an electrical circuit connecting said automatic

switch to said cut-off devices whereby said cut-off devices may be electrically operated, the circuit between said automatic switch and controlling motor being so controlled by said automatic switch that the direction of rotation of motor may be varied, the operation of said circuit closing device controlling the switch shuttles of said automatic switch, substantially as described. 20
